UNITED STATES PATENT OFFICE.

GEORGE C. SETCHELL, OF NORWICH, CONNECTICUT.

METHOD OF PRODUCING DIES FOR MAKING WOOD TYPE.

SPECIFICATION forming part of Letters Patent No. 389,113, dated September 4, 1883.

Application filed April 2, 1882. Serial No. 269,314. (No model.)

To all whom it may concern:

Be it known that I, GEORGE C. SETCHELL, a citizen of the United States, residing at Norwich, in the county of New London and 5 State of Connecticut, have invented a certain new and useful Improvement in Methods of Producing Dies for Making Wood Type, which improvement is fully set forth and described in the following specification, reference being 10 had to the accompanying sheet of drawings.

This invention is in the class of dies used for impressing or indenting end wood, as in wood-type making, and has for its object the improvement or development of the 15 methods by which such dies are produced.

My said improvement has special reference to dies of the kind described in a patent to William H. Page, issued December 20, 1887, and numbered 374,993. Under the said Page 20 system dies are produced by utilizing the enlarged pattern-letters commonly used in the production of wood type by cutting-machines. To the backs of such patterns are secured ribs conforming in relative position to the 25 outline of the letter on the front. The pattern thus produced is then placed in a pantograph-machine and used to control the movement of the cutting-tool while a fac-simile letter (or die) is cut in metal. This provides a die 30 which when pressed into a block of wood leaves projecting portions the reverse of the desired print; in fact, forms a printing-type substantially like those commonly produced by cutting-machines. As compared with the said 35 Page system, my present invention has in its favor the ability to use pattern-letters without specially preparing the reverse ribs above referred to; and, further, I am able to produce dies with beveled or inclined edges, sometimes 40 desirable, but not easily attained by the Page method.

I have illustrated the several stages necessary in producing dies by my new method in the annexed sheet of drawings, which, with 45 the following description, fully explain said method, so that one familiar with the arts of wood type and die making may readily produce the same.

Figure 1 of said drawings represents the 50 enlarged pattern necessary to produce a die for the letter B. Fig. 2 is a perspective view of a solid die made in a pantograph-machine

by using the said pattern to control the movement of the cutting-tool. Fig. 3 is an edge view of said die having brazed to its face a 55 block of brass or similar metal. Fig. 4 shows the same after having been separated on line $x\ x$ of Fig. 3. Fig. 5 is a face view of the die as it then appears ready for use. In Fig. 6 I have shown a block of type-wood impressed 60 by said finished die, and in Fig. 7 a print from a type so made.

The pattern-letter a (shown in Fig. 1) is usually cut in hard wood somewhat larger than the desired die, so that any imperfections 65 in said pattern will be lost sight of in the reduced die. After having produced in a pantograph-machine a solid die of the form indicated by the reference-letter c in Fig. 2, I secure to the face of said solid die (preferably by 70 brazing) a metal plate or block, d , of sufficient thickness and size to support the operative portions of the die—that is, those projecting portions which are to be forced into the wood in the act of type-making. I then remove the 75 original backing by sawing through on line $x\ x$ of Fig. 3, thus reversing the outline of the operative portions or face of the die, as shown in Fig. 5. The die thus formed may be used to produce a great number of type by simply 80 indenting or impressing blocks of prepared type-wood.

It is sometimes desirable to produce a die with undercut edges. To accomplish this by 85 my new method a cutter whose end portion is tapered, or shaped approximately as a frustum of a cone, may be used in the production of the solid die c . When the die is reversed by the brazing and sawing operation above described the finished die is left with the desired 90 undercut.

Having described my invention, I claim—

The improvement in methods of producing impression dies, which consists of forming a reverse die from an enlarged pattern in a pantograph-machine, in brazing to the face of 95 said die a block of metal, and finally in removing the original backing, in the manner and for the purpose specified.

GEORGE C. SETCHELL.
